PLANT PROTECTOR

Robert J. Rosenvold and Lloyd K. Rosenvold, both of 1101 Main St., Montrose, Colo.

Filed Nov. 1, 1963, Ser. No. 77,233

Term of patent 14 years

(Cl. D35—1)

FIG. 1 is a perspective view of our new design for a plant protector.

FIG. 2 is a top plan view of the plant protector shown in FIG. 1.

FIG. 3 is a bottom plan view of the plant protector shown in FIG. 1.

FIG. 4 is a side view in elevation of the plant protector in FIG. 1.

FIG. 5 is a sectional view taken on the line 5—5 of FIG. 2 taken in the direction indicated by the arrows.

We claim:

The ornamental design for a plant protector, as shown and described.
